UNITED STATES PATENT OFFICE.

GUY J. GLENN, OF IMBLER, OREGON.

GRAIN-SHOCKER.

1,124,416.

Specification of Letters Patent. Patented Jan. 12, 1915.

Application filed June 20, 1914. Serial No. 846,342.

To all whom it may concern:

Be it known that I, GUY J. GLENN, a citizen of the United States, residing at Imbler, in the county of Union and State of Oregon, have invented certain new and useful Improvements in Grain-Shockers, of which the following is a specification, reference being had to the accompanying drawings.

10 This invention relates to certain improvements in grain shockers and has relation more particularly to a device of this general character especially designed and adapted to be secured to and travel with a grain binder of the usual construction; and the object of the invention is to provide a device of this general character having novel and improved means whereby the bundles, after being received from the binder, are 15 delivered in proper position upon a shock forming table, such table being capable of movement to discharge such shock upon the ground.

20

The invention consists in the details of construction and in the combination and arrangement of the several parts of my improved grain shucker, whereby certain important advantages are attained and the device is rendered simpler, less expensive 25 and otherwise more convenient and advantageous for use, all as will be hereinafter more fully set forth.

The novel features of the invention will be carefully defined in the appended claims.

30 In order that my invention may be the better understood, I will now proceed to describe the same with reference to the accompanying drawings, wherein—

Figure 1 is a side elevational view of a shucker constructed in accordance with an embodiment of my invention; Fig. 2 is a longitudinal vertical sectional view taken through the device as disclosed in Fig. 1, with certain of the parts in different positions; Fig. 3 is a top plan view of the device as herein included; Fig. 4 is an enlarged detail view in plan of the operating means for the chute members herein included; Fig. 5 is an enlarged detail sectional view of the additional details included in the operating means for the chute members; and Fig. 6 is a somewhat dia-grammatic view, partly in section and partly in elevation, illustrating the coaction be-

tween the dividing board and shock receiver 55 as herein embodied.

As disclosed in the accompanying drawings, 1 denotes a supporting axle, on which are operatively mounted the traction wheels 2 and projecting forwardly of the axle 1 60 is the frame 3, to the forward extremity whereof is operatively connected the draper 4, the upper stretch whereof travels inwardly toward the axle 1 on an upward incline. The forward end of the frame 5 65 of the draper has suitably secured thereto a yoke 6 with which is operatively engaged a caster wheel 7 which may be of any ordinary or preferred construction. The draper 4, as herein disclosed, is directed around 70 the rollers 8 and 9, the roller 8 being positioned adjacent the rear of the frame 5 and having an extremity 10 projecting exteriorly of the frame 5, and to such projected portion is secured a sprocket 11 75 around which is disposed a sprocket chain 12 which is also directed around an idler sprocket 11^a supported in a bracket 10^a on the side of the frame 5. In mesh with the chain 12 is a sprocket 14 fixed to a shaft 80 15 disposed transversely of the frame 3. One end of the shaft 15 projects to one side of the frame 3 and to such projected portion is suitably affixed a sprocket 15', around which is disposed a sprocket chain 85 16 which is also directed around a sprocket wheel 17 fixed to the axle 1 whereby it will be perceived that the draper 4 will be caused to properly travel.

Rotatably supported by the frame 1 rearwardly of the draper 4 is the vertically disposed shaft 18 having suitably affixed to the upper extremity thereof the disk 19 and pivotally engaged with said disk 19 at diametrically opposite points are the upper 90 ends of the chute members 20, with each of which coacts a spring member 21 operatively supported by a second disk 22 fixed to the shaft 18 which tends to force and maintain the chute 20 normally on a requisite incline relative to the draper 4, so that a sheaf, being carried by the draper, may be properly accommodated within the chute, for a purpose which will hereinafter be 95 more particularly set forth.

100 Fixed to the lower extremity of the shaft 18 is a gear wheel 23 adapted to mesh with a gear wheel 24 of a diameter equal to twice

the diameter of the gear 23. Alined with the gear 24 but out of mesh therewith is a second gear 25 of equal diameter which is adapted to mesh with a gear 26 loosely mounted on a shaft 27 operatively engaged with the shaft 1 through suitable gearing 28. The shaft 27 is adapted to rotate continuously during the travel of the machine. The gears 24 and 25 are united by the pitman 29, the operative connection 30 between the pitman 29 and the gear 24 being a distance from the axial center of the gear 24 substantially equal to twice the distance between the pivotal connection 31 between the pitman 29 and the gear 25 from the axial center of the gear 25. By this arrangement, it will be seen that upon a complete revolution, in a manner to be hereinafter described, of the gear 26, the gear 25 will make a one-half revolution while the gear 24, under the influence of the pitman 29, will make a one-fourth turn in one direction and result in a half turn of the gear 23 and of the shaft 18. The next complete revolution of the gear 26 will result in a similar operation of the gears 23, 24 and 25, except that the gear 23 will be caused to rotate in an opposite direction. The extent of rotation of the gear 23 may be controlled by adjusting the pivotal connections 30 and 31 of the gears 24 and 25, respectively, relative to the axial centers of said gears.

Keyed to the upper extremity of the shaft 27 but capable of movement longitudinally thereof relative to the gear 26 is a clutch member 32 adapted to coact with the gear 26 to cause the same to rotate in unison therewith. The clutch member 32 is provided in its periphery with an annular groove 33 adapted to accommodate the yoke 34 carried by the rock arm 35 operatively supported by a cross strap 36 connected with the draper frame 5. Operatively engaged with the lever 35 is an arm 37 which is pivotally connected with the upwardly directed lever 38 by the link 37a. The lever 38 is operatively engaged by a rod 39 leading to an upwardly disposed rearwardly movable pivot trip 40 with which the lower extremity of a chute 50 is adapted to contact after a sheaf has been delivered thereto by the draper 4, it being understood that the weight of the sheaf is such as to overcome the tension of the coacting spring 21. The rearward movement of the draper, as is believed to be self-evident, will result in the engagement of the clutch member 32 with the gear 26 and cause the chute 20 to be rotated in one direction in order to deliver a sheaf upon the shock carrier 41, to be hereinafter more particularly referred to. This movement will result in the second chute 20 being properly positioned relative to the draper 4 to receive the following sheaf whereby the operation, hereinbefore mentioned, will be repeated, ex-

cept that the second sheaf will be carried in an opposite direction.

As herein disclosed, the shock carrier 41 consists of duplicate sections, each comprising a plurality of elongated spaced bars projecting rearwardly of the frame 3, and the carrier 41 has its inner extremity operatively engaged with the draper frame 5 through the medium of the links 42, whereby it will be readily perceived that each of the sections may be swung either into receiving or discharging position. Projecting rearwardly of the shaft 1 and rotatably supported thereby are the arms 43 which overlie each of the sections of the carrier 41 and have their outer extremities pivotally engaged by the link 44 which in turn is pivotally engaged with the section whereby it will be readily perceived that upward pull upon the arms results in the carrier assuming the requisite receiving position. As I do not wish to be understood as limiting myself to any particular means whereby the shock carrier may be maintained in its receiving position, it is thought that a detailed disclosure thereof is unnecessary.

Projecting upwardly from the frame 3 rearwardly of the axle 1 but in close proximity thereto are the posts 45 with which is slidably engaged the dividing board 46 normally disposed at a predetermined distance above the carrier 41 and of a length substantially equal to the length of the carrier. The dividing board 46 is of a weight in excess of the table or carrier 41 alone but is less than the combined weight of the shock and table or carrier and when such carrier or table 41 is released so as to fall to the ground, said dividing board is adapted to move upwardly so that it will be released or disengaged from the tops of the bundles or sheaves and, as herein disclosed, this is accomplished by connecting with said dividing board 46 adjacent its rear end a flexible member 47 passing up and around a sheave 48 operatively engaged with the upstanding rearwardly curved bars 49, herein disclosed as anchored to the draper frame 5. The flexible member 47 is directed downwardly and operatively engaged, as indicated at 50, with the sections of the shock carrier 41, as is believed to be clearly shown in the accompanying drawings, and whereby it will be readily perceived that as the carrier 41 drops, the dividing board 46 will be elevated. It will also be readily perceived that when the shock is discharged from the carrier 41 the weight of the dividing board 46 will serve to automatically return said carrier to its receiving position.

In order to maintain the bundles or sheaves against lateral displacement from the carrier 41 during the forming of a shock thereon, I find it of advantage to employ the rearwardly disposed substantially par-

allel spring members 51 disposed above the opposite longitudinal marginal portions of the carrier 41 and having their inner extremities connected to the curved arms 49 5 and their intermediate portions supported by the supplemental posts 52 projecting upwardly from the frame 5, or more particularly by the table 54 supported thereby. It might be well at this time to state that the 10 gears 23, 24, 25 and 26, hereinbefore referred to, are also operatively supported directly below this table 54.

It will also be obvious that my invention is susceptible of some change and modification 15 without material departure from the principles and spirit thereof and for this reason I do not wish to be understood as limiting myself to the precise arrangement and formation of the several parts herein 20 shown in carrying out my invention in practice.

In order that the grain which falls from the straw at the time of its delivery from the draper 4 to the carrier 41 may not be 25 lost, I position below the adjacent extremities of the draper 4 and the carrier 41 the pan 55 which serves for a purpose which is believed to be self-evident.

I claim:

30 1. A device of the character described comprising a suitably supported draper, a carrier acting in conjunction therewith, a chute interposed between the draper and the carrier, said chute being movable around a vertical axis and movable in a vertical plane, and means under control of the vertical movement of the chute for imparting movement thereto around a vertical axis.

2. A device of the character described 40 comprising a suitably supported draper, a carrier acting in conjunction therewith, a vertically disposed shaft interposed between the draper and carrier, a disk fixed to the shaft, a chute pivotally engaged with the 45 disk and depending therefrom, and means under control of the chute for imparting axial rotation to the shaft.

3. A device of the character described 50 comprising a suitably supported draper, a carrier acting in conjunction therewith, a vertically disposed shaft interposed between the draper and carrier, a disk fixed to the shaft, a chute pivotally engaged with the disk and depending therefrom, means under 55 control of the chute for imparting axial rotation to the shaft, and means carried by the shaft coacting with the chute for maintaining the same in an inclined position.

4. A device of the character described 60 comprising a draper, a carrier acting in conjunction therewith, a chute mounted for swinging and rotary movement, and mechanism for imparting rotary movement to the

chute, said mechanism including a controlling trip engageable by the chute upon 65 swinging movement thereof in one direction.

5. A device of the character described comprising a suitably supported draper, a carrier acting in conjunction therewith, a vertically disposed shaft interposed between 70 the draper and the carrier, diametrically opposed chutes pivotally supported by said shaft and adapted to rotate therewith, and power driven means for imparting rotation to the shaft alternately in opposite directions. 75

6. A device of the character described comprising a suitably supported draper, a carrier acting in conjunction therewith, a dividing board positioned above the carrier, 80 a vertically disposed shaft interposed between the draper and the carrier, diametrically opposed chutes pivotally engaged with the shaft and movable therewith, and means for imparting rotation to the shaft alternately in opposite directions whereby one 85 chute is adapted to deliver to one side of the dividing board and the second chute to the opposite side thereof.

7. A device of the character described 90 comprising a draper, a carrier acting in conjunction therewith, a chute mounted for swinging and rotary movement, mechanism for imparting rotary movement to the chute, said mechanism including a controlling trip 95 engageable by the chute upon swinging movement thereof in one direction, and means for normally maintaining the chute out of engagement with the trip.

8. A device of the character described 100 comprising a suitably supported draper, a carrier acting in conjunction therewith, a vertically disposed shaft interposed between the draper and the carrier, a chute pivotally supported by the shaft and adapted to rotate 105 therewith, a spring carried by the shaft and coacting with the chute for normally maintaining the chute in one position, and power driven means for imparting rotation to the shaft alternately in opposite directions. 110

9. A device of the character described 115 comprising a suitably supported draper, a carrier acting in conjunction therewith, a chute interposed between the draper and the carrier, said chute being movable around a vertical axis and movable in a vertical plane, and adjustable means under control of the vertical movement of the chute for imparting movement thereto around a vertical axis. 120

In testimony whereof I hereunto affix my signature in the presence of two witnesses.
